(57) **CLAIM**

The ornamental design for a screwdriver key-tag, substantially as shown and described.

DESCRIPTION

FIG. 1 is a top view of the screwdriver key-tag of the present invention. The bottom view of the screwdriver key-tag of the present invention is a mirror image of FIG. 1.

FIG. 2 is a right side top perspective view of the screwdriver key-tag of the present invention.

FIG. 3 is a left side bottom view of the screwdriver key-tag of the present invention; and,

FIG. 4 is a cross-section view of the screwdriver key-tag of the present invention, presented solely to illustrate the depression in the center portion of the screwdriver key-tag of the present invention. Applicant explicitly disclaims any internal features of the cross-section view of FIG. 4.
